No. 700,899.

Patented May 27, 1902.

J. H. CLARK.

TROLLEY WHEEL.

(Application filed Sept. 11, 1901.)

(No Model.)

UNITED STATES PATENT OFFICE.

JOHN H. CLARK, OF UHRICHSVILLE, OHIO.

TROLLEY-WHEEL.

SPECIFICATION forming part of Letters Patent No. 700,899, dated May 27, 1902.

Application filed September 11, 1901. Serial No. 74,989. (No model.)

To all whom it may concern:

Be it known that I, JOHN H. CLARK, a citizen of the United States, residing at Uhrichsville, in the county of Tuscarawas and State 5 of Ohio, have invented certain new and useful Improvements in Trolley-Wheels; and I do hereby declare that the following is a full, clear, and exact description of the same, reference being had to the annexed drawings, 10 making a part of this specification, and to the figures of reference marked thereon, in which—

Figure 1 is a side elevation. Fig. 2 is an edge view. Fig. 3 is a section of the wheel 15 and its head. Fig. 4 is a detached view of one of the axle-boxes. Fig. 5 is a view showing a portion of one member of the head and illustrating one of the axle-boxes placed in proper position. Fig. 6 is a similar view showing the axle-box and retaining-plate removed.

The present invention has relation to trolley-wheels; and it consists in the different parts and combination of parts hereinafter described, and particularly pointed out in the 20 claim.

Similar numerals of reference indicate corresponding parts in all the figures of the drawings.

In the accompanying drawings, 1 represents 25 the shank of an ordinary trolley-pole, which shank is provided with the bifurcated end composed of the two members 2 and 3, which members are spaced one from the other a distance sufficient to allow room for the trolley-wheel 4. The periphery of the trolley-wheel 35 4 is of the usual construction and is provided with an ordinary groove 5 for the reception of the usual trolley-wire.

The trolley-wheel 4 is provided with the 40 integral axle 6, or, if desired, the axle may be formed separate and connected to the trolley-wheel 4 in any convenient and well-known manner; but to carry out the object and purpose of the present invention the axle 6 must 45 necessarily rotate with the trolley-wheel and not remain at rest, or, in other words, the trolley-wheel 4 is not to revolve upon the axle.

Upon the outer sides of the members 2 and 3 are located chambers 7, which chambers are 50 formed by the spherical flanges 8. Upon the inner faces of each of the members 2 and 3

of the trolley-wheel head proper are formed the grooves 9, and of course the grooves 9 are located directly opposite each other. The grooves 9 are for the purpose of receiving and 55 holding in proper position the axle-boxes 10, which axle-boxes are formed of such a length that they will span the chambers 7, by which arrangement the ends of the axle 6 are located in the chambers 7, substantially as illustrated 60 in Fig. 3.

For the purpose of securely holding the boxes 10 in fixed position and also preventing any accidental displacement of the boxes the retaining-bars 11 are provided, which retaining-bars are preferably seated into recesses 65 12, which recesses are formed upon the upper sides of the head members 2 and 3, and said plates held in fixed position by lug-bolts 13 or their equivalents. The upper ends of the 70 boxes 10 are provided with the beveled ends 14 and are beveled at such an angle that they will be parallel with the retaining-bars 11 when said retaining-bars are brought or placed into their fixed position. 75

It will be understood that by providing the removable retaining-bars 11 they can be taken off, after which the boxes 10 are free to be removed, together with the wheel 4 and its axle, this object being desired for the purpose of making repairs or for any other purpose when it is desired to remove the trolley-wheel 4 from its head proper. 80

Within the chambers 7 is located what is commonly called "waste" or other oil-absorbing substance, and in use oil is applied to the waste through the oil-holes 15 and 16, a sufficient amount of oil being applied at a single time to thoroughly saturate the waste. By this arrangement the axle of the trolley-wheel 90 will remain properly lubricated for a considerable length of time, thereby doing away with the necessity of frequently oiling the axle.

It will be understood that after the boxes 95 10 have been placed in position the waste will be securely held in the chambers 7. It will also be understood that the axle 6 should be provided with the flanges 18, the ends of which flanges come against the inner faces of 100 the boxes 10, this being necessary in order to prevent any end movement of the axle.

Having fully described my invention, what I claim as new, and desire to secure by Letters Patent, is—

The combination of a trolley-wheel provided with an axle rotatable with said trolley-wheel, a trolley-head consisting of members spaced one from the other and each of the members provided with a chamber, there being a groove located in the inner faces of the head members and communicating with the chambers, axle-boxes located in the

grooves and over the openings and means for holding the axle-boxes in fixed position, substantially as and for the purpose specified.

In testimony that I claim the above I have 15 hereunto subscribed my name in the presence of two witnesses.

JOHN H. CLARK.
